UNITED STATES PATENT OFFICE.

WILLIAM J. GOOCH, OF FRANKLIN, KENTUCKY.

DESIGN FOR A KITCHEN-CABINET.

SPECIFICATION forming part of Design No. 26,883, dated April 13, 1897.

Application filed September 30, 1896. Serial No. 607,503. Term of patent 7 years.

To all whom it may concern:

Be it known that I, WILLIAM J. GOOCH, a citizen of the United States, residing at Franklin, in the county of Simpson and State of Kentucky, have invented a new and original Design for Kitchen-Cabinets, of which the following is a specification.

This invention relates to a new and original design for kitchen-cabinets; and it has for its object to provide a design of this character that shall be both useful and ornamental.

The leading feature of the design resides in a kitchen-cabinet having a box-like base portion provided with a flat top, a pair of large upright cylindrical bin-bodies rising from the flat top of the base portion near opposite ends thereof and provided at the top with bell-shaped caps having central circular raised portions, a pair of smaller upright cylindrical bodies rising from the flat top of the base portion between and in front of the large cylindrical bin-bodies at one side of the vertical centers of the latter, said smaller cylindrical bodies having their adjacent sides extended inwardly to form a central reentrant space, a central upright flat body-panel disposed between the said smaller cylindrical bodies and extending the full length thereof, said body-panel having a vertically-alined series of circular figures provided with offstanding irregular projections, a horizontal cap-plate arranged at the top of the smaller cylindrical bodies and the body-panel and provided with a curved front edge conforming to the curvature of said smaller cylindrical bodies and the reentrant space therebetween, and also with oppositely-located pairs of circular projections, and a pointed crest-piece disposed between the caps of the bin-bodies and provided with a circular figure therein.

In the drawing the figure is a perspective view of a kitchen-cabinet embodying the herein-described design.

Referring particularly to the drawing, the numeral 1 designates the base portion of the cabinet, which is somewhat in the form of a cubical box and is provided with a flat top 2 and a compoundly-curved front side 3, bounded at its opposite side edges by the sigmoidally-curved lines 4, which are in the form of rounded beads. The compoundly-curved front sides 3 of the box-like base portion 1 is

formed with a single long rectangular door-panel 5, extending the entire length of the base portion and provided with an offstanding circular knob 6 and a raised rectangular bead 7. Above the plane of the panel 5 the front side 3 of the base 1 is further formed with a plurality of smaller rectangular door-panels 8, arranged in horizontal alinement and provided with offstanding circular knobs 9 and raised rectangular beads 10.

Rising from the flat top 2 is a pair of oppositely-located large upright cylindrical bodies 11, provided at the top with bell-shaped tops 12, having central circular raised portions 13, and arranged between and in front of the bodies 11, at one side of the vertical centers thereof, is a pair of oppositely-located smaller cylindrical bodies 14, having their adjacent sides extended inwardly to form a central reentrant space. Within this reentrant space between the bodies 14 is located a central upright flat body-panel 15, extending the full length of the bodies 14 and formed at its lower end with rectangular door-plates 16^a, of different sizes. The panel 15 is also provided with a vertically-alined series of circular figures 16, the lowermost pair of which are of a greater diameter than the others, and all of which figures 16 are provided with offstanding irregular projections 17. A horizontal cap-plate 18 is arranged at the top of the bodies 14 and the panel 15 and is provided with a curved front edge conforming to the curvature of the bodies 14 and the reentrant space therebetween. Said cap-plate 18 is also provided with oppositely-located pairs of circular projections 19, and in rear of the cap-plate 18, between the caps 12, is disposed an inverted-V-shaped crest-piece 20, having scalloped edges 21 and provided therein with a circular figure 22.

What I claim is—

The design for a kitchen-cabinet herein shown and described.

In testimony that I claim the foregoing as my own I have hereto affixed my signature in the presence of two witnesses.

WILLIAM J. GOOCH.
